US00D380273S

United States Patent [19]

Emerson et al.

[11] Patent Number: Des. 380,273

[45] Date of Patent: **Jun. 24, 1997

[54] AUTOMATED DIAGNOSTIC ASSAY MACHINE

[75] Inventors: **Rick E. Emerson; Robert L. Lathrop, Jr.**, both of San Jose; **Donald R. Reichel**, Saratoga; **Ronald K. Lion**, Watsonville, all of Calif.

[73] Assignee: **Becton Dickinson and Company**, Franklin Lakes, N.J.

[**] Term: 14 Years

[21] Appl. No.: 36,811

[22] Filed: Mar. 24, 1995

[51] LOC (6) Cl. 24-01

[52] U.S. Cl. D24/232; D10/81; D24/186

[58] Field of Search D24/233, 231, D24/186, 169; D10/81; 422/100, 102, 81, 62, 63, 68.1, 67

[57] CLAIM

The ornamental design for an automated diagnostic assay machine, as shown and described.

DESCRIPTION

FIG. 1 is a front elevational view of an automated diagnostic assay machine showing our new design;

FIG. 2 is a rear elevational view of the automated diagnostic assay machine as shown in FIG. 1;

FIG. 3 is a left side elevational view of the automated diagnostic assay machine shown in FIGS. 1 and 2;

FIG. 4 is a right side elevational view of the automated diagnostic assay machine shown in FIGS. 1-3;

FIG. 5 is a top plan view of the automated diagnostic assay machine shown in FIGS. 1-4;

FIG. 6 is a bottom plan view of the automated diagnostic assay machine shown in FIGS. 1-5; and,

FIG. 7 is a front perspective view of the automated diagnostic assay machine shown in FIGS. 1-6.
